UNITED STATES PATENT OFFICE.

JOHN MICHAEL CALLOW, OF SALT LAKE CITY, UTAH, ASSIGNOR TO METALS RECOVERY COMPANY, OF AUGUSTA, MAINE, A CORPORATION OF MAINE.

PROCESS OF AND APPARATUS FOR CONCENTRATING ORES.

1,258,869.

Specification of Letters Patent.

Patented Mar. 12, 1918.

Application filed February 4, 1915, Serial No. 6,089. Renewed August 1, 1917. Serial No. 183,980.

To all whom it may concern:

Be it known that I, JOHN M. CALLOW, a subject of the King of Great Britain, residing at Salt Lake City, in the county of Salt Lake and State of Utah, have invented certain new and useful Improvements in Processes of and Apparatus for Concentrating Ores, of which the following is a specification.

- 10 My invention relates to a process of and apparatus for the concentration of metallic ores by separating the metallic particles from the barren or rocky constituents thereof. Primarily, my invention comprises the 15 combination with a separatory cell in which the separation of metalliferous from non-metalliferous particles occurs by flotation of the values, of a means in advance of and connecting with said cell for effecting a preliminary separation of coarse material, or 20 gangue from fines and delivering the separated fines into the receiving or head-end of the separatory cell whereby the matter discharged from the preliminary separator 25 is in turn acted upon by flotation to separate the metalliferous from the associated non-metalliferous material and to recover the former, as I will hereinafter describe and claim.
- 30 The present invention is specifically related to the art commonly known as the flotation art. In that art one type of flotation processes consists in adding an oil, or an oil and an acid, or an oil and an alkali, or 35 some other substance capable of producing froth, to the finely ground ore pulp and water, and then subjecting the mixture to violent agitation under such conditions that large volumes of air are beaten into the 40 mixture, whereupon a thick permanent froth is produced wherein the mineral particles of the ore or a large portion of them are collected and retained, and are ultimately recovered as a concentrate. In another 45 type of flotation processes carried on in apparatus, one exemplification of which is illustrated in the present application, the mixture of water and finely ground ore pulp in which the oil, oil and acid, oil and alkali, or 50 other modifying agent has been incorporated, is subjected to the aerating or gasify-

ing action of bubbles of gas or air, which, entering at the lower portion of the mixture rise through it and levitate to the surface thereof, carrying with them the mineral constituents of the ore and passing over into the launder or collecting trough in the form of an evanescent foam radically distinct in its physical characteristics from the thick froth incident to the beating of the mixture in the flotation processes above referred to.

In both of these types of flotation processes it is desirable to relieve the separatory cell in which the flotation of the mineral particles occurs from much of the heavy work incident to the presence of an excess of coarse material in the ore pulp. The present invention is intended to effect this preliminary separation of such coarse material, thereby enabling the finer mineral particles or values to be more expeditiously recovered from the associated non-metalliferous material or gangue, and imposing upon the separatory cell a lesser amount of work than would otherwise be imposed upon it. Accordingly, a leading object of the present invention is to provide a process of and a means for separating the coarser material from the fines before the ore pulp is subjected to flotation.

In the accompanying drawings forming part of this specification I have illustrated one type of apparatus for carrying out my invention and wherein—

Figure 1 is a vertical sectional view partially in elevation of a separatory cell and a preliminary separator associated therewith.

Fig. 2 is a top plan view showing the feed pipe omitted.

In the accompanying drawings, A, represents a separatory cell which may be of any desired form and construction, but which for illustrative purposes is shown as being substantially rectangular and having an inclined bottom, a, with a tailings discharge, b, at the lower end, said tank having suitably supported above its bottom a false floor or bottom, B, of some suitable porous material, such for instance as porous brick, or in fact any substance or material through which

2
air, or other gaseous medium may be forced, said porous medium permitting the passage of the gaseous medium but not water and pulp, and the gaseous medium being admitted under pressure into a compartment or compartments, C, below the porous floor, and being delivered therethrough and into the pulp in the form of jets of infinite number and fineness, for the purpose of thoroughly gasifying the pulp composed of crushed ore, water and a frothable agent. The gas or air bubbles, in rising through the pulp come in contact with the mineral particles, and levitating to the surface, serve as a carrier for the mineral particles and appear on the top of the liquid as a foam which overflows into a suitable launder or other receptacle.

During the described gassing of the pulp, which may be produced by any method known in this art, the non-metalliferous particles settle upon the inclined porous floor and gravitate thereover toward the tailings or discharge end, b, which action of the particles is facilitated by the discharge of the gaseous medium through the aforesaid porous bottom.

In order to relieve the separatory cell of some of the work imposed upon it, it is desirable to effect a preliminary gassing separation of coarse from fine material and to deliver the separated fine material only into the separatory cell where it is further and immediately treated by flotation. To this end, I associate with the head end of the separatory cell, some appropriate form of separator, which in the present instance is shown as including a tank or vessel, D, into which the crushed ore and water are delivered through a feed spout, E, or other appropriate means, said tank having a conical lower portion and a tailings or separating chamber, F, at its bottom and having an overflow or launder, G, at its upper end, said launder having its discharge leading into the head end of the separatory cell, A, just above the higher end of the inclined porous floor, B, thereof.

A suitable valve-controlled pipe, H, connects with the lower part of the separating chamber, F, and is designed to conduct a gaseous medium, for instance, air, or water, into the lower portion of the pulp contained within said chamber with the result that this gaseous upcast column serves to partly gasify the pulp and classify the same; in other words, to separate the fine from the coarser particles by elevating the former and overflowing the same into the launder, G, for delivery into the head end of the separatory cell, where the material is immediately treated by flotation as heretofore described.

The coarser particles admitted into the preliminary separating chamber may be removed through an outlet, U, of any suitable character and may be rejected, or it may be sent to some other vessel or apparatus for further treatment.

By the foregoing process and the means described or the mechanical equivalents thereof I am enabled to effect a preliminary gassing and classification of the pulp, and by separating the coarse particles or sands, from the finer mineral bearing particles prior to sending the latter to the separatory cell, A, I am permitted to relieve the separatory cell of undesirable foreign matter and at the same time facilitate the recovery of the value contained in the pulp admitted to said cell.

Having thus described my invention what I claim as new and desire to secure by Letters Patent is:—

1. The combination with a flotation cell having means for producing bubbles which act to separate by flotation the metalliferous particles of an ore mixture from the non-metalliferous particles thereof, of a vessel for initially receiving the mixture, said vessel having an overflow from its upper portion into the cell and having a tailings separating chamber in the lower portion, and means for delivering gaseous fluid connecting with said vessel for separating the coarse from the fine particles of the mixture before flotation and previous to the admission of the fine particles to said cell for flotation, said separating chamber having a tailings outlet.

2. The flotation process herein described which consists essentially, in separating the coarse from the fine particles of a mixture containing powdered ore and a frothable agent, by preliminarily subjecting the mixture to the action of a gaseous column and thereby separating the coarse particles and substantially immediately flowing the fine metalliferous particles and some of the fluid constituents of the mixture into a separate vessel, and then substantially immediately thereafter subjecting said separated fine metalliferous and non-metalliferous particles in said separate vessel to gasifying to form bubbles which separate by flotation the metalliferous from the non-metalliferous particles.

3. The flotation process herein described which consists, essentially, in separating the coarse from the fine particles of a mixture containing powdered ore, water and a frothable agent, by preliminarily subjecting the mixture to the action of an upcast gaseous column to thereby separate the fine particles from the coarse particles and overflowing the fine particles and lighter non-metalliferous particles and some of the fluid constitu-

ents of the mixture into a separate flotation cell; and then substantially immediately subjecting said separated metalliferous and non-metalliferous particles in said cell to
5 gasifying to form bubbles which separate by flotation the metalliferous from the non-metalliferous particles.

In testimony whereof I affix my signature in presence of two witnesses.

JOHN MICHAEL CALLOW.
